UNITED STATES PATENT OFFICE.

SETH H. LEAVENWORTH, OF CINCINNATI, OHIO, ASSIGNOR TO THE HOMAN SILVER PLATE COMPANY, OF SAME PLACE.

DESIGN FOR SILVERSMITHS' STOCK.

SPECIFICATION forming part of Design No. 32,331, dated March 13, 1900.

Application filed February 2, 1900. Serial No. 3,755. Term of patent 3½ years.

To all whom it may concern:

Be it known that I, SETH H. LEAVENWORTH, a citizen of the United States, residing at Cincinnati, in the county of Hamilton and State 5 of Ohio, have invented and produced a new and original Design for Silversmiths' Stock; and I do hereby declare the following to be a full, clear, and exact description of the same, reference being had to the accompanying 10 drawings, forming a part thereof.

My invention comprises a design for silversmiths' stock to be used for ornamenting various articles of silverware, plated ware, &c., and is clearly shown in the accompanying 15 drawings, wherein—

Figure 1 is a front elevation of silversmiths' stock embodying said design, and Fig. 2 is a plan of the same.

B represents full-blown trumpet-flowers at one end of a vine. A and C are trumpet- 20 blossoms at the other end of said vine.

I claim as my invention—

The design for silversmiths' stock, substantially as herein shown, and described.

In testimony whereof I affix my signature 25 in presence of two witnesses.

SETH H. LEAVENWORTH.

Witnesses:

JAMES H. LAYMAN,
ERNEST G. SIMON.
